NEW YORK, ASSIGNEES TO RUBBER REGENERATING COMPANY, A CORPORATION OF
INDIANA.

TREATMENT OF MATERIALS.

1,211,370.

Specification of Letters Patent. Patented Jan. 2, 1917.

Application filed April 24, 1915. Serial No. 23,653.

To all whom it may concern:

Be it known that we, RAYMOND B. PRICE and WILLIAM J. STEINLE, both citizens of the United States, and residents, respectively, of New York, county of New York, and State of New York, and Elmhurst Heights, county of Queens, State of New York, have invented certain new and useful Improvements in Treatment of Materials, of which the following is a full, clear, and exact description.

This invention relates to the treatment of materials, more particularly rubber, rubberlike or similar materials, and has for an object essentially exhausting, compacting, and giving final formation to the material, such treatment, so preparing the product for vulcanization that it may be vulcanized without the usual wrappings or other supports and will not "blow" during vulcanization.

The invention may be carried out in many different ways, and in one embodiment requires that the material being treated shall be subjected to the action of a vacuum, and the exhausted material compacted and fed in the nature of a surface coating upon a form partaking of the configuration of the desired article. For example, in the manufacture of hollow articles such as hose, inner tubes, and the like, the exhausted and compacted material may be fed as a coating upon a mandrel which travels at substantially the rate of discharge of the exhausted and compacted material. Subsequently the mandrel with the tube of material thereon may be put into a vulcanizer and the material vulcanized without wrapping the same with fabric which is the usual practice.

40 An apparatus suitable for carrying out the invention is shown in the accompanying drawing in which—

Figure 1 is a longitudinal sectional view of the apparatus; Fig. 2 is a detail view of the carriage; Fig. 3 is a detail view of the mandrel connection; Fig. 4 is a fragmentary sectional view showing a modified form of the invention.

In the drawing, 10 designates a cylindrical casing which is supported in horizontal position by supports 11 at the ends of the casing. Mounted for free rotation in the casing is a feed-screw 12, which is formed at one end with a spindle 13 that is journaled 55 in a bearing 14 on the casing, there being

a drive pulley 15 fixed to the spindle for rotating the feed-screw. The feed-screw terminates at its free end short of the discharge end of the casing as shown, and may there be supported, as for instance, by a 60 spider, if desired. The feed-screw diminishes in pitch toward its free end, whereby the material advancing upon the feed-screw is crowded and thereby compacted at the discharge end of the casing. The casing is provided at the intake end with a hopper 16 within which is mounted a positive feeding means such as rollers 17, although this mechanism may be varied at will, as for instance, a feed-screw or other desired positive feeding means may be substituted, or even this feeding means may be dispensed with altogether. The casing is provided at the discharge end with a die 18 which is formed centrally with an opening 19 of a 70 shape conforming to the configuration of the article to be formed, in the present instance the opening having a circular wall to impart a like configuration to the product. A mandrel 20 coacts with the wall of the 75 die opening 19, in forming the product, which in this instance is a tube, the mandrel being received into and fed longitudinally through a bore 21 formed in the feed-screw 12. The speed at which the mandrel is fed 80 through the feed-screw is preferably the same as the speed of the material discharged through the die opening, although the mandrel may be fed at any speed ratio relatively to the discharge of the material without departing from the spirit or sacrificing 85 any of the advantages of the invention.

For exhausting entrapped fluids, gases and the like from the material, the same is subjected to the action of a vacuum through 90 a pipe 22 which may be located at any desired point in the casing, but in the present embodiment is shown disposed near the feed hopper whereby the material will be most effectively acted upon by the vacuum while 100 still in its semi-divided condition, that is, before it becomes compacted by the diminished pitch of the free end of the feed screw.

The process is preferably carried on continuously, and for this result a plurality of 105 mandrels are fed through the feed-screw in single file, that is the rear end of one mandrel will be in abutting contact with the forward end of the next succeeding mandrel. To accomplish this, we preferably provide a 110

pair of superposed feed rollers 23 which may be driven from any suitable source of power and are formed to receive therebetween and push a mandrel forwardly 5 through the bore of the feed-screw, a suitable support, such as a roller 24, being arranged in advance of the feed rollers 23 to support and guide the mandrels.

It is desirable that each mandrel with its 10 coating of exhausted, compacted material be supported as it emerges from the machine and to accomplish this, we preferably provide a carriage 25 having an orificed end 26 that grasps the end of the mandrel and supports the mandrel during its passage from the machine. The confronting ends of the mandrels are preferably formed to interfit as at 27, so that after the mandrel has left the machine, it will not drop down but will 15 be supported by the next following mandrel until the operator cuts the tube at the end of the ejected mandrel and separates the mandrels.

In practice, the exhausted compacted material is fed through the circular wall of the 25 die opening and meeting the traveling cylindrical mandrel is caused to surround and adhere to the mandrel in the nature of a constantly elongating tube. The mandrel may be passed through the die opening any number of times to build plies of the material thereon, if desired. As a result of the exhausting and compacting treatment, the tube 30 formed upon the mandrel will be compact, homogeneous, and substantially free from entrapped fluids, gases, voids and the like, such condition of the material rendering it incapable of blowing during cure. To complete the process, each mandrel with the 35 tube of material thereon, is placed in a vulcanizer and cured, preferably in open heat, but may be cured in any usual or preferred manner, and during cure is preferably not wrapped with muslin or other wrappings as 40 is the usual practice. After cure the tube is removed from the mandrel manually, by compressed air, or by other usual or preferred means.

It is not of course essential that the mandrel be passed through the feed-screw, or

that the feed-screw even be hollow, since, as shown in Fig. 4, a feed-screw 28 without a bore may be mounted within the casing 29 and the mandrel 30 may be fed at a right angle to the axis of the feed-screw, as shown, 55 the mandrel being fed through the discharge opening 31 of the die 32 by the means illustrated in Fig. 1, or by any other desired means.

Having described our invention, what 60 we claim and desire to protect by Letters Patent is:

1. An apparatus for treating material embodying a casing, means for feeding the material into the casing, a form, a member in 65 the discharge end of the casing having a discharge opening permitting of the passage of the form therethrough, the wall of said opening being spaced from the form in all directions, means for feeding the form 70 through the opening; means for exhausting the material, and a feed screw in the casing for feeding the exhausted material in contact with said wall and the traveling form.

2. An apparatus for treating material embodying a casing, a hollow feed-screw for advancing the material in the casing, a form receivable in the bore of the feed-screw, means for feeding the form through said bore, a suction pipe for exhausting the material, and a die at the discharge end of the casing having an opening permitting of the passage therethrough of the form with a 75 coating of the exhausted material thereon.

3. An apparatus for treating material embodying a casing, a feed-screw in the casing; means for exhausting the material advanced by the feed-screw, a mandrel, means for moving the mandrel past the feed-screw, and a die at the delivery end of the casing 80 having an opening for permitting the passage therethrough of the mandrel with a 85 surface coating of the compacted exhausted material thereon.

Signed at New York, N. Y., this 16" day 95 of April, 1915.

RAYMOND B. PRICE.
